UNITED STATES PATENT OFFICE

NED C. L. BROWN, OF SCOTTSVILLE, NEW YORK, ASSIGNOR TO GENERAL RAILWAY SIGNAL COMPANY, OF ROCHESTER, NEW YORK

CAR RETARDER FOR RAILROADS

Application filed December 26, 1930. Serial No. 504,675.

This invention relates in general to car retarders of the track brake type, such as used in classification yards and the like, and has more particular reference to means whereby the effectiveness of the total weight of a car in producing retardation on the car wheels, can be readily varied.

In retarders of the character in question, it is desirable to be able to readily vary the degree of retardation to be applied to a car, in order to care for differences in speeds and weights of cars, and also desired distances of travel of cars after leaving the retarder.

According to the present invention, means are provided for shifting the pivot point of each one of a series of levers, whereby to vary the effectiveness of the weight of a car in producing retardation on the car wheels.

Further objects, purposes and characteristic features will appear as the description progresses, reference being made to the accompanying drawings, showing, solely by way of example and in no manner in a limiting sense, one form which the invention can assume. In the drawings:—

Fig. 1 is a top plan view of a retarder in accordance with the present invention.

Fig. 2 is a sectional elevation on line 2—2 of Fig. 1, viewed in the direction of the arrows.

Fig. 3 is a sectional elevation on line 3—3 of Fig. 1, viewed in the direction of the arrows.

Fig. 4 is a fragmentary sectional elevation on line 4—4 of Fig. 1 viewed in the direction of the arrows.

Fig. 5 is a section on line 5—5 of Fig. 1, viewed in the direction of the arrows.

Referring now to the drawings, there are shown two track rails 1, constituting a stretch of single track on which are represented car wheels 2. Supported by the ballast, are wooden ties 3 running transversely of the track rails in the usual manner, with channel caps 4 thereon for rockingly sup-

porting the inner rockers 5 of a pair of rockers for each track rail, the outer rockers being designated as 6. The pairs of rockers 5 and 6, for each running rail, are tied together by cross beams or yokes 7, of a general U-shape, there being pivoted shoe beam arms 8 and 9 pivoted as at 10 and 11 respectively, to the rockers 6 and 5. Each shoe beam arm carries a shoe beam 12, and a brake shoe 13, the shoe beams and brake shoes either being continuous or articulated. They are shown continuous in Fig. 1, but can be articulated if desired as in Patent 1,757,428, granted to W. K. Howe on May 6, 1930.

Each of the shoe beams is received in a slot formed between the base of the running rail and angle irons 14, clamped to the web of the rail, whereby to constrain the brake shoes, shoe beams and pivoted shoe beam arms to move vertically with the running rails. The rails and interconnected parts are held in their normal position by means of plungers 30, upwardly pressed by springs 15 sleeved thereon.

The arrangement of parts as above described produces at each running rail, a toggle joint with the arms of the toggle constituted by the brake beam arms 8 and 9, with the joint opening upwardly and closing downwardly, whereby any weight carried by the running rails tends to close the jaws of the toggle joint and press the braking faces of the retarder shoes against the sides of the car wheels carried by the running rails.

The ties 3, carrying the inner rockers 5, are positioned to have their upper faces considerably below the bases of the running rails, so that they normally do not support the rails, the rails being carried at these points by means of the brake beam arms 8 and 9.

The outer rocker 6 of each pair of rockers associated with a running rail, is carried in a groove 16, in a lever L, which has a slot 17 in its lower face to receive one roller 18,

of a carriage constituted by the roller 18 and two rollers 19, which latter can move in a direction parallel to the running rails to thereby vary the point of contact 20, between 5 the roller 18 and the lever L. The carriage constituted by the rollers 18 and 19 can be moved on its supporting plate 21, by means of an adjusting rod 22, operated by a motor M, through a shaft 23 carrying a crank 24 10 and an interconnecting link 25, all for the purpose of varying the effectiveness of the weight of a car in producing retardation on the car, as will be explained below.

At the other end of each of the levers L, is 15 a second groove 26, in which are supported trunnions 27, fastened to the ends of transverse steel ties 28, the steel ties being spaced so that there is one such tie for each pair of carriage and lever organizations. The steel 20 ties 28 are positioned with their upper faces 29 considerably higher than the top faces of the ties 3 whereby to normally support the weight of the track rails 1, and any load thereon, as shown most clearly in Fig. 4.

It is thus seen that at spaced intervals, 25 there are steel ties 28 positioned high enough to normally support the track rails, with the ends of these steel ties terminating in trunnions 27 carried in grooves 26 of the levers 30 L, these ties 28 being spaced up above any other support, so that they are free to move downwardly and thus allow the track rail to move downwardly, if the lever L is rocked about its support point 20.

With the arrangement of parts as above 35 described, it can readily be seen that if the motor M be operated to move the carriage to the left, as seen in Fig. 3, so that roller 18 lies directly beneath trunnion 26, the entire 40 weight of a train passing over the running rails is transmitted directly down through the track rails, the ties 28, the trunnions 27, and the rollers 18 and 19 to the ballast. In this case no weight is supported by the brake 45 beam arms 8 and 9, so that the toggle joints formed by these members have no tendency to close and exert retardation on the passing car wheels. Thus, with the carriage moved to a position directly beneath the trunnions 50 27, no retardation is experienced by a passing car.

On the other hand, if the carriage is moved 55 to the right, so as to bring the pivot point 20 directly beneath the rocker 6, then the steel ties 28 are free to move downwardly far enough to relieve them of supporting any weight of the passing car, so that all of the weight of the car is carried by the rockers 5 and 6. In such circumstances, the brake 60 beam arms 8 and 9 are moved downwardly, together with the running rails 1, to thereby close the toggle joint and press the brake shoes into tight frictional engagement with the sides of the car wheels, until the various 65 forces involved come to a balance.

In the case just considered, if w is the weight supported by the rocker 6, then the force, f , with which each of the brake shoes 13 is pressed against its side of the car wheel 2, is equal to the weight, w , multiplied by 70 the ratio of the lever arms

$\frac{a}{b}$.

The lever arms a and b are shown, in Fig. 75 2, to be the rotation arms about the pivot points 10 and 11. We can thus see that, with the carriage positioned directly beneath the rockers 6, the entire weight supported by the rockers, which is the entire weight on the track rails, is effective in producing retardation. 80

As the carriage is moved away from directly beneath the rocker 6, and towards the trunnions 27, a portion of the total weight carried by the track rails is carried by the steel ties 28, and this portion is not effective in producing retarding forces on the passing car wheels. Accordingly, the nearer the carriage is moved to the position directly below the trunnions 27, the less effective is the total weight in producing a retarding force. For example, if the pivot point 20 is midway between the rocker 6 and the trunnion 27, the retarding force is just half of what it is when the pivot point 20 is directly beneath the rocker 6. Again, if the carriage is moved three-quarters of the distance toward trunnions 27 the retarding force is one-quarter of the maximum for a given weight of car. 95

When it is desired that a car pass through the retarder wholly free from retardation, and out of contact with the brake shoes 13, the carriage can be moved until the pivot point 20 lies to the left of the trunnions 27, as viewed in Fig. 3, whereupon the lever L can rock in a clockwise direction so as to lower the pivot points 10, and cause the toggle joint constituted by the brake beams 8 and 9 to open up and move the brake shoes away from the track rails, the flanges 12¹ on the brake beams 12, being slidable in and out of the slots between the base of the rails and the angle irons 14. 105

The above arrangement of parts thus constitutes a retarder wherein the retardation effected on passing car wheels, is produced by the weight carried by the wheels so that any tendency of the car wheels to climb out from between the brake shoes decreased the degree of retardation momentarily to prevent the climbing out. 110

The structure above described also provides means whereby the total weight of a car, or a series of cars, is carried from either one or both of two sets of points, these points being the trunnions 27 and the rockers 6, together with means constituted by the carriage including the rollers 18 and 19 for causing the total weight to be carried by either one of 115 120 125 130 135

these sets of points alone, or by both of them in varying ratios. As described above, the effectiveness of the total weight in producing retardation depends upon where this weight is supported, it being fully effective when it is supported from rocker 6, and being wholly ineffective, or in other words, there being no retardation, when it is supported by trunnions 27, and being intermediately effective according as the support is shifted from the rockers to the trunnions.

The above rather specific description of one form of the present invention, is given solely by way of illustration, and is not intended, 15 in any manner whatsoever, in a limiting sense. Obviously, the invention can assume many different physical forms, and is susceptible of numerous modifications, and all such forms and modifications, as come within 20 the scope of the appended claims, are intended to be covered by this application.

Having described my invention, I now claim:—

1. In a car retarder of the track brake type, 25 in combination, an arm pivoted at each side of a track rail and extending inwardly and upwardly with its inner end adjacent the rail, brake shoes on the inner ends of the arms in position to be moved against the sides of a passing car wheel, means connecting the inner ends of the arms to the track rail to carry the track rail, the arms forming a normally open toggle joint which closes upon 30 downward movement of the rail.

2. In a car retarder of the track brake type, in combination, an arm pivoted at each side of a track rail and extending inwardly and upwardly with its inner end adjacent the rail, brake shoes on the inner ends of the arms in position to be moved against the sides of a passing car wheel, means laterally 40 connecting the inner ends of the arms to the track rail to carry the track rail, the arms forming a normally open toggle joint which closes upon downward movement of the rail.

3. In a car retarder of the track brake type, in combination, an arm pivoted at each side of a track rail and extending inwardly and upwardly with its inner end adjacent the rail, a brake shoe on the inner end of each arm in position to be moved against the sides of a passing car wheel, means connecting the inner ends of the arms to the track rail to carry the track rail, the arms forming a normally open toggle joint which closes upon downward movement of the rail, and means for shifting the point of support of a load carried by said rail from a point 50 at the toggle joint to a point remote therefrom, whereby to vary the force, produced by a given rail load, tending to close the toggle and press the shoes inwardly against the sides of a car wheel.

4. In a car retarder of the track brake type,

in combination, an arm pivoted at each side of a track rail and extending inwardly and upwardly with its inner end adjacent the rail, brake shoes on the inner ends of the arms in position to be moved against the 70 sides of a passing car wheel, means connecting the inner ends of the arms to the track rail to carry the track rail, the arms forming a normally open toggle joint which closes upon downward movement of the rail, an 75 adjusting lever, means supporting the weight of the rail at the toggle joint from one end of the lever, a support tie normally in contact with the track rail and carried by the other end of said lever, and a movable pivot point support for the lever.

5. In a car retarder of the track brake type, in combination, an arm pivoted at each side of a track rail and extending inwardly and upwardly with its inner end adjacent the rail, brake shoes on the inner ends of the arms in position to be moved against the sides of a passing car wheel, means laterally 80 connecting the inner ends of the arms to the track rail to carry the track rail, the arms forming a normally open toggle joint which closes upon downward movement of the rail, an adjusting lever, means supporting the weight of the rail at the toggle joint from one end of the lever, a support tie 85 normally in contact with the track rail and carried by the other end of said lever, and a pivot point support for the lever.

6. In a car retarder of the track brake type, in combination an arm pivoted at each side of a track rail and extending inwardly and upwardly with its inner end adjacent the rail, brake shoes on the inner ends of the arms in position to be moved against the sides of a passing car wheel, means connecting the inner ends of the arms to the track rail to carry the track rail, the arms forming a normally open toggle joint which closes upon downward movement of the rail, an 100 adjusting lever, means supporting the weight of the rail at the toggle joint from one end of the lever, a support tie normally in contact with the track rail and carried by the other end of said lever, and a carrying 105 pivot point support for the lever, movable from one end of the lever to the other, to thereby vary the ratio of the rail loads supported by the toggle joint and the support tie.

7. In a car retarder of the track brake type, in combination, an arm pivoted at each side of a track rail and extending inwardly and upwardly with its inner end adjacent the rail, brake shoes on the inner ends of the arms in position to be moved against the sides of a passing car wheel, means connecting the inner ends of the arms to the track rail to carry the track rail, the arms forming a normally open toggle joint which closes upon downward movement of the rail, an adjusting 115 lever, means supporting the weight of the 120 rail at the toggle joint from one end of the lever, a support tie normally in contact with the track rail and carried by the other end of said lever, and a movable pivot point support for the lever, movable from one end of the lever to the other, to thereby vary the ratio of the rail loads supported by the toggle joint and the support tie.

8. In a car retarder of the track brake type,

rail at the toggle joint from one end of the lever, a support tie normally in contact with the track rail and carried by the other end of said lever, and a carrying pivot point support for the lever, movable from one end of the lever to the other to thereby vary the ratio of the rail loads supported by the toggle joint and the support tie, the pivot point being movable beyond the first point where the rail load is wholly carried by the support tie.

8. In a car retarder of the track brake type, in combination, an arm pivoted at each side of a track rail and extending inwardly and upwardly with its inner end adjacent the rail, brake shoes on the inner ends of the arms in position to be moved against the sides of a passing car wheel, means laterally slidingly connecting the inner ends of the arms to the track rail to carry the track rail, the arms forming a normally open toggle joint which closes upon downward movement of the rail, an adjusting lever, means supporting the weight of the rail at the toggle joint from one end of the lever, a support tie normally in contact with the track rail and carried by the other end of said lever, and a pivot point support for the lever, the pivot point support comprising a movable carriage supported from the ground, and means to move the carriage to different positions beneath the adjusting lever.

9. In a car retarder of the track brake type, in combination, an arm pivoted at each side of a track rail and extending inwardly and upwardly with its inner end adjacent the rail, brake shoes on the inner ends of the arms in position to be moved against the sides of a passing car wheel, means connecting the inner ends of the arms to the track rail to carry the track rail.

In testimony whereof I affix my signature.
NED C. L. BROWN.
